US00D989716S

(12) **United States Design Patent** (10) **Patent No.:** **US D989,716 S**
(45) **Date of Patent:** **** Jun. 20, 2023**

(54) **CABLE**

(71) Applicant: **Shenzhen Diyiwei Electronics Co., Ltd.**, Shenzhen (CN)

(72) Inventor: **Lei Yan**, Shenzhen (CN)

(73) Assignee: **Shenzhen Diyiwei Electronics Co., Ltd.**, Shenzhen (CN)

(**) Term: **15 Years**

(21) Appl. No.: **29/805,056**

(22) Filed: **Aug. 24, 2021**

(30) **Foreign Application Priority Data**

Aug. 20, 2021 (EM) 008657191-0001

(51) **LOC (14) Cl.** **13-03**

(52) **U.S. Cl.**

USPC **D13/153**

(58) **Field of Classification Search**

USPC D13/153, 133, 147, 154; D14/433
See application file for complete search history.

(57) **CLAIM**

The ornamental design for a cable, as shown and described.

DESCRIPTION

FIG. 1 is a perspective view of a cable showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the cable that form no part of the claimed design.

1 Claim, 7 Drawing Sheets

FIG. 1

FIG. 2

FIG. 3

FIG. 4

FIG. 5

FIG. 6

FIG. 7

FIG. 8
